TRAIN CONTROL SYSTEM

Application filed July 29, 1926. Serial No. 125,652.

This invention relates broadly to railway signaling systems. More particularly the invention relates to signaling systems in which train carried circuits and devices are adapted to receive and give indications of track conditions.

The system disclosed in the present application is directed to railway induction signaling systems. By induction signaling systems I mean such systems in which there is no mechanical or electrical contact between the train carried devices or circuits and the roadside devices or circuits. The indications are transmitted from the roadside to the train apparatus through the ether or by disturbances in the ether. Such disturbances may be caused by magnetic devices, electro-magnetic devices, or by electrical induction devices disposed on the roadside and on the train.

One of the objects of the present invention is to provide an inductive signaling system of the type described above, which is capable of receiving and giving both a danger and a caution indication.

Another object of the invention is to provide a three-position roadside inductor which is capable of giving three indications. The three indications are preferably clear, caution and danger.

Another object of the invention is to make the operation of the roadside apparatus responsive to track conditions.

A still further object of the invention is to provide a train carried inductive device which is prompt in its response to the condition of the road-side apparatus without any appreciable time lag.

Another object of the invention is to utilize a diaphragm of magnetic material which is disposed in a magnetic field of force for the operation of circuit makers and breakers.

A further object of the invention is to provide pneumatic means for the transmission of the vibrations of the diaphragm to the circuit making and breaking means.

The above objects are accomplished by utilizing a diaphragm of magnetic material disposed in the field of force of a strong

train carried magnet. The diaphragm is preferably disposed in such a manner as to bridge the space between the poles of the magnet. The magnet, however, holds the diaphragm normally under tension in a distended position. This magnet cooperates with roadside devices which under danger conditions have the effect of reducing the flux that passes between the poles of the magnet or through the diaphragm whereby the tension on the diaphragm is reduced and the same snaps back to a less distended position. The same roadside piece of apparatus is also capable of bringing about an increase in the field of force passing between the poles of the magnet or through the diaphragm when it is in a caution indication condition. Under such conditions the diaphragm will be attracted more strongly to the magnet and will therefore be distended even further.

Another and smaller diaphragm is connected to the first diaphragm by means of a body of fluid preferably compressed and the vibrations of the larger diaphragm are transmitted to and magnified by the smaller diaphragm. Contact making and breaking devices are operated by the vibrations of the smaller diaphragm in order to operate the danger and caution circuits carried by the train:

The roadside device shown in the present application is an improvement on similar types of device well known in the art. The roadside inductor comprises a body of magnetic material disposed in the roadside in such a manner that when a train passes thereover, the train carried magnet will pass immediately over the roadside device. Such devices as known hitherto have been capable of giving only two indications, namely a danger and a clear indication. In the present invention this device is capable of giving three indications, the three indications being clear, caution and danger. The roadside inductor gives a danger indication when it is in its inert state. In this condition it serves to receive a substantial portion of the flux passing between the poles of the train carried magnet when said magnet passes thereover,

and thereby transmits a danger indication to the train.

When the winding mounted on the roadside body is short-circuited on itself, it gives a clear indication. Under such conditions it serves to reflect the flux passing between the poles of the train carried magnet and said flux is practically undisturbed. The result is that the conditions of the train carried circuit are undisturbed. In the third position a source of energy is connected to the winding on the roadside body. This puts the roadside body in an inductively repellent state which constitutes the caution indication of the roadside body. In this condition the roadside body serves to strengthen the flux passing between the poles of the train carried magnet when the latter passes over the roadside body. The train carried circuits are thereby disturbed to give a caution indication.

The invention will be more clearly understood by reference to the accompanying drawings and the description thereof.

In the drawings:

Figure 1 is a diagrammatic illustration of the roadside apparatus.

Figure 2 shows the train carried apparatus and its relationship to the roadside inductor.

Figure 3 shows a side view of the train carried and roadside inductors.

Figure 4 shows a modification of the system.

Figure 5 shows a further modification of the system.

Figure 1 shows a signalling block A and portions of the immediately preceding and next succeeding blocks. This figure also shows a part of a block signalling circuit that is commonly associated with block signals and for the operation thereof. Only that part of the block signalling circuit is shown herein which cooperates with the roadside inductor shown herewith.

The three-position roadside inductor which constitutes a part of the invention to which the present application is directed, consists primarily of a body of magnetic material 10. As shown in Figure 3, this body 10 is preferably shaped in such a manner as to present wide pole shoes N and S. The body 10 is provided with a winding 11. One side of the winding 11 is connected by means of conductor 12 to a movable contact 13 while the other side is connected by means of wire 14 to one side of a battery 15. The contact 13 is movable and may be put in one of the three positions indicated. In the dotted line position *a* shown in Figure 1, the movable contact 13 closes the circuit through the winding 11 including the battery 15. Under such conditions the winding 11 will carry a current and the body 10 will be magnetized to present the two poles N and S as shown in Figure 3. In the *b* position of the contact

13 the winding 11 is short-circuited by means of wire 16 without the application of any source of energy to the winding. In the *c* position of the contact 13 the winding 11 is open-circuited.

By means of the three positions which the contact 13 is capable of assuming, the inductor 10 may give any one of three indications. When the contact 13 is in its *c* position and the winding 11 is open-circuited, the body 10 may be said to be in its inert state and is designed to give a danger indication to any passing train. When the contact 13 is in the *b* position and the winding 11 is short-circuited through the wire 12, contact 13, wires 16 and 14, the roadside inductor 10 together with the winding 11 may be said to be in an inductively reflective state and will give a clear indication. When the contact 13 is in its *a* position whereby an electromotive force is impressed upon the winding 11, the body 10 is magnetized presenting N and S poles to train carried devices. The roadside inductor is then in an inductively repellent state and indicates caution. The manner by which these three indications of the roadside inductor are picked up by a passing train will be explained hereinafter.

For the present, consideration is limited to the three-position roadside inductor 10 and the manner in which the inductor may be controlled so as to give any one of the three indications in accordance with the track conditions.

Referring to Figure 1, A shows a signaling block of the railroad tracks 17 and 18. The block is provided with a track battery 19 and the track relay 20. The block signaling circuit comprises a battery 21, pole changer 22, polarized control relay 23, and wires connecting the battery to the control relay. The control relay is normally energized by the following circuit: battery 21, pole changer 22, wire 24, track relay armature 25, wire 26, control relay 23, and return wire 27. Contact 13 is a polarized armature and is controlled by the control relay 23. When the block A and the next succeeding block are unoccupied, the relay 23 is energized by the circuit traced immediately above and the polarized armature 13 occupies the *b* position. Under such conditions the roadside inductor 10 is in its inductively reflective state and will give a clear indication. When a train enters block A the track magnet 20 will be deenergized, its armature 25 will open the block signaling circuit and consequently the polarized relay 23 will be deenergized. The polarized contact 13 will then drop to its *c* position, thereby opening the circuit of the winding 11 of the roadside inductor 10. The roadside inductor will thereby be put into its inert state and will give a danger indication. When the train that occupied block A passes out of block A into the next succeeding block, the semaphore

28 will be put into its stop position by means of the block signaling circuit of that block in the manner well known in the art. The movement of the semaphore 28 to its stop position will shift the pole changer 22 from the position shown in Figure 1 to its dotted line position and the control relay 23 will then be energized through the following circuit: battery 21, pole changer 22, wire 24, magnetic armature 25, wire 26, polarized relay 23, return wire 27, wire 29, pole changer 22, and back to battery. The polarized relay 23 is now energized in the direction reverse to normal. Then the contact 13 will be attracted to its *a* position whereby the battery 15 will be imposed upon the winding 11 of the roadside inductor 10. Under such conditions the roadside inductor 10 will be put in its inductively repellent state and will give a caution indication.

It will be seen, therefore, that by means of the devices shown in Figure 1, the roadside inductor 10 is capable of giving three indications depending upon the track conditions and that such indications are automatic with relation to the track conditions. I do not, however, wish to be limited to the specific manner of operation of the inductor 10 shown in this figure. The armature 13 may be controlled by other means than the means shown herein and the block signaling circuit may be designed in any manner known in the art.

I shall now proceed to describe the inductor carried by the train which is designed to cooperate with the roadside inductor and to pick up the indications given by the roadside inductor. Broadly the train carried inductor comprises a strong magnet and a large diaphragm of magnetic material disposed within the field of force created by the magnet in such a manner that the diaphragm is constantly under tension and in distended position. The train carried magnet 30 is provided with large faced poles N' and S' and the magnet is mounted on the train in such a manner that as the train passes by the roadside inductor 10, the pole faces N' and S' will pass immediately over the roadside inductor 10. When the magnet passes over the roadside inductor 10, the flux passing between the poles of the train carried magnet or the flux that passes through the magnetic diaphragm and serves to hold it in its tensioned or distended position, will be varied depending upon the condition of the roadside inductor. If the roadside inductor is in its inert state, that is if the contact 13 is in its *c* position and the circuit of the roadside inductor is open, the proximity of the body of magnetic material 10 to the train carried magnet will cause a substantial portion of the flux passing between the poles of the train magnet or through the diaphragm to be deflected from its normal path and pass through the body 10. The attractive influence of the

train carried magnet upon the diaphragm will then be reduced. The tension under which the diaphragm is normally maintained will be decreased and the diaphragm will snap back to a position which more nearly approximates the natural position. In my invention this movement of the diaphragm is utilized to operate circuit making and breaking devices which in turn control signaling circuits on the train.

Referring now to Figure 2 which shows a specific embodiment of my invention, 31 shows a track rail mounted on a railroad tie 32 and 33 indicates the wheel of a train passing over said track. The train carries the magnet 30 which may be a strong permanent magnet, or if desired, may be energized by the winding 34. The magnet is preferably of the horse shoe type of magnet having large faced legs 35 and 36 which are provided with pole faces N' and S'. A hermetically sealed casing 37 preferably of non-magnetic material is mounted on a face of the legs 35 and 36 in such a manner as to bridge the space between the legs. A diaphragm 40 is mounted in the casing in a plane parallel to the plane of the magnet, thereby dividing the casing 37 into the two chambers 38 and 39. The chamber 39 is connected by means of conduit 41 to a source of compressed air. A narrow air leak 95: passage 42 connects the two chambers.

Another hermetically closed box 43 is carried by the train at a point away from the influence of the magnet 30. On the bottom of this box is disposed the cup shaped receptacle 44 provided with an aperture 45 in the center of the bottom thereof. A flexible tubing 71 preferably of steel, connects the cup shaped receptacle 44 and the chamber 38 of the casing 37. The receptacle 44 is covered with a thin diaphragm 46. The receptacle 44 is preferably of insulating material.

A light bracket 47 of conducting material is mounted on the center of the diaphragm 46. This bracket carries two contact making elements 48 and 49 which are electrically connected to the bracket 47. The receptacle 44 carries two spring contacts 50 and 51 which are insulated from each other and which are normally in contact with 49 and 48 respectively.

The train also carries two signaling circuits, one of said circuits being designed to receive the caution indication and the other of said circuits being designed to receive the stop indication. The two circuits have a common return wire 52 in which the source of energy 53 is connected by means of wire 54. The source of energy 53 is connected to the bracket 47. The other wire 55 of the caution receiving circuit is connected to the spring contact 51. The other side 56 of the danger receiving circuit is connected to a fixed contact 57 which is fixedly mounted with relation to the magnet 30 and is preferably 130

mounted on the body of the magnet and reaches into chamber 39. The fixed contact 57 normally abuts against a contact 58 in the center of the diaphragm 40. The wire 59 connects the contact 58 with the spring contact 50.

The elements operated by the signaling circuits are diagrammatically illustrated as 60 and 61, the element 61 being connected between the conductors 52 and 55. Normally elements 60 and 61 are both energized and when so energized produce or indicate a "clear" condition. The deenergization of element 61 leaving only the energization of element 60 produces or indicates a "caution" condition, and conversely, the deenergization of element 60 leaving only an energization of element 61 produces or indicates a "danger" condition.

20 The operation of the system shown in Figures 1, 2 and 3 is as follows: The compressed air of the air brake system is allowed to enter chamber 39 of casing 37 to the right of the iron membrane. This compressed air leaks 25 into chamber 38 through the narrow air leak passage connecting the two chambers. The compressed air therefore passes by means of the flexible connection 45 into the receptacle 44 and through the narrow air leak passage 30 70 into the box 43.

From what has been said in an earlier portion of this specification, the operation of the system shown in Figures 1 to 3 will be apparent. Assuming that the block A and 35 the block ahead are unoccupied, the contact 13 will occupy its *b* position and the winding 11 will be short-circuited, and the inductor will give a clear indication. As the train passes over the inductor 10 and the 40 poles of the magnet 30 pass over the poles of the inductor 10, the inductor will serve to reflect the flux conditions that exist between the poles 35 and 36 and the diaphragm 40 and so will retain its normal position and the 45 normally closed caution and danger indication circuits will not be operated. If, however, the block A is occupied and the polarized control relay 23 is deenergized, the contact 13 will occupy its *c* position and the 50 winding 11 will be open-circuited. The inductor 10 is now in its inert condition and will give a danger indication. When the train magnet 30 reaches a position overlying the inductor 10, the flux passing between the 55 legs 35 and 36 and passing through the diaphragm 40 will be partly deflected through the inductor 10 with the result that the attractive influence of the magnet upon the diaphragm 40 will be lessened and the diaphragm 40 will retract from the position shown to a position to the left thereof. This sudden contraction of the diaphragm 40 will cause an impulse to be transmitted through the tubing 71 to the diaphragm 46. In view 60 of the fact that the diaphragm 46 is several

times smaller than the diaphragm 40, the movement of said diaphragm 46 will be considerably amplified and the bracket 47 together with the contacts 48 and 49 will be moved upward. This will result in the breaking of the danger circuit between the contacts 49 and 50 and the operation of the indicator 60 producing a "danger" indication.

If, however, the block A is unoccupied and the next succeeding block is occupied, the pole changer 22 will occupy its dotted line position and the control relay 23 will be energized in the reverse direction. The contact 13 will then occupy its *a* position and the inductor 10 will be energized by the battery 15 and winding 11.

When the train under these conditions reaches a position wherein the train magnet overlies the inductor 10, the influence of the magnetic flux created by the inductor 10 will be such as to strengthen the flux passing between the legs 35 and 36 of the train carried magnet, and will strengthen the flux passing through the diaphragm 40 with the result that the influence of the magnet upon the diaphragm will be increased and the latter will be moved to a more distended position to the right of the normal position. This sudden distension of the diaphragm 40 will cause a correspondingly magnified movement of the diaphragm 46 downwardly, with the result that the caution indication circuit will be broken between the contacts 48 and 51, and the indicator 61 alone will be operated producing a "caution" condition. The contacts 57, 58 are not essential to the operation of the system. They are inserted, however, as a safety device or as a detector to detect any possible leaks to the atmosphere from the chamber 38 or from the box 43.

Should such a defect arise, the compressed air in chamber 39 will force the diaphragm 40 to the left and the danger indication circuit will be open between the contacts 57, 58. If a leak occurs in the air chamber 39 on the right of the diaphragm, it can do no harm to the system if the leak is small as the air pressure will still be considerable. If, however, the leak in the air chamber 39 is of such a size as to reduce the air pressure therein to a considerable extent, the train will be automatically stopped in the same way and by the same means as are provided in systems wherein shoe stems operable by air pressure are utilized in connection with ramp systems that is to say, the said chamber is connected to the air brake system.

If a leak to atmosphere occurs in the hermetically closed box 43, the pressure below the thin diaphragm 46 will be greater than the pressure above the thin diaphragm and this fact will bring about an opening of the danger indication circuit between the contacts 49, 50.

While it is not essential for the operation of this system that compressed air be utilized

125

130

and while atmospheric air may be utilized in the system, I prefer to use compressed air for the reason that it constitutes a better medium for transmitting the pressure wave from the diaphragm 40 to the diaphragm 46. The transmission will be much stronger by means of compressed air than when atmospheric air is utilized.

The danger indicator 61 may be of any type desired and may be of the well known type wherein its operation effectuates the application of the brakes on the train.

While I have shown that the contact 13 may be operated by the polarized relay 28, it is obvious that the same contact may be operated by the semaphore 72. The semaphore 72 is of the type that is commonly used in block signalling systems and is designed to give three indications by the three different positions of the semaphore arm. The three indications of the semaphore arm are clear, caution and danger. It is obvious that the contact 13 may be so connected to the semaphore arm that in its clear position the circuit of the winding 11 will be short-circuited on itself, in the caution position of the semaphore arm the winding 11 may be connected through a battery and in the danger position of the semaphore arm the winding 11 may be connected through a battery and in the danger position of the semaphore arm the winding 11 may be open-circuited.

Figure 4 of the drawings shows a modification of the system in which the roadside inductor is capable of giving only two indications, namely, the indications of clear and danger. The battery 15 may be omitted in this system if desired. The roadside inductor will under these conditions give a clear indication when the winding 11 is short-circuited, and will give a danger indication when the winding 11 is open-circuited. It is obvious, however, that if desired the clear indication may be given by inserting a source of energy in the circuit of the winding 11.

In the system shown in Figure 4, a train carries only one signalling circuit, namely, the danger indication circuit. The devices utilized in this system on the train are identical with those described in the system shown in Figures 1-3 except for the fact that the small diaphragm 46 carries only one contact making element and the cup shaped receptacle 44 carries only one fixed contact. These two contacts 49, 50 are in the danger receiving circuit which is identical with the danger receiving circuit shown in Figure 2. In this system, therefore, a danger indication will be picked up by the train when it passes the roadside inductor under such conditions when the winding of the roadside inductor is open-circuited. If the winding of the roadside inductor is short-circuited or is connected to a source of energy, the inductor

gives a clear indication and the train carried circuit will not be disturbed when the train passes over the inductor under such conditions.

Figure 5 shows a system similar to that shown in Figure 4 except that instead of utilizing compressed air for transmitting the impulse from the large diaphragm 40 to the small diaphragm 46, air at atmospheric pressure is utilized for the same purpose. The construction and arrangement of the train carried devices in this system are substantially identical with that shown in Figure 4 except that the box 43 is eliminated and the contacts 57 and 58, which are designed in the preceding systems to give a danger indication in case of a leak in the system, are also eliminated. Otherwise, the system shown in Figure 5 operates in the same manner as that shown in Figure 4.

What I claim:

1. In a train control system, in combination with a vehicle carried inductor, a roadside three position apparatus comprising an element of magnetic material for giving a danger indication when in its inert state, a winding on said element and circuit means for said winding for imparting to said element an inductively reflective state to give a clear indication and for imparting to said element an inductively repulsive state to give a caution indication.

2. In a train control system, in combination with a vehicle carried inductor, a roadside three position indicator comprising an element of magnetic material, a winding on said element, a circuit for said winding, and selective switch means for short circuiting said winding and for connecting a source of energy to said winding.

3. In a train control system, in combination with a vehicle carried inductor, a roadside three position indicator comprising an element of magnetic material, a winding on said element, a circuit for said winding, and selective switch means operable in accordance with track conditions for short circuiting said winding and for connecting a source of energy to said winding.

4. In a train control system, in combination with a vehicle carried inductor, a roadside three position indicator comprising an element of magnetic material, a winding on said element, a circuit for said winding, and selective switch means responsive to track conditions for short circuiting said winding and for connecting a source of energy to said winding.

5. In an inductive railway signaling system, a magnet, a signaling circuit, a diaphragm held under the influence of the magnet, and pneumatic means controlled by the diaphragm whereby a variation in the magnetic flux between the poles of the magnet will open the signaling circuit.

6. In an inductive railway signaling system, a magnet, a normally closed signaling circuit, a diaphragm of magnetic material mounted on the poles of the magnet and 5 pneumatic means whereby a movement of the diaphragm will open the signaling circuit. 79
7. In an inductive railway signaling system, an induction device, a normally closed 10 signaling circuit, a diaphragm under tension held under the influence of the induction device, and pneumatic means whereby a movement of the diaphragm will operate the signaling circuit. 75
15. 8. In an inductive railway signaling system, an induction device, a diaphragm held under the influence of the device, a second diaphragm held away from the influence of the induction device and means whereby a 20 movement of the first diaphragm will cause a corresponding movement in the second diaphragm. 80
9. In an inductive railway signaling system, an induction device, a diaphragm held 25 under the influence of the device, a second diaphragm held away from the influence of the induction device and means whereby a movement of the first diaphragm will cause a corresponding magnified movement in the 30 second diaphragm. 85
10. In an inductive railway signaling system, an induction device, a diaphragm held under the influence of the device, a second diaphragm held away from the influence of 35 the induction device and pneumatic means whereby a movement of the first diaphragm will cause a corresponding movement in the second diaphragm. 90
11. In an inductive railway signaling system, an induction device, a diaphragm held under the influence of the device, a second diaphragm, and a body of fluid connecting 40 the diaphragms. 95
12. In an inductive railway signaling system, an induction device, a diaphragm held under the influence of the device, a second diaphragm, and a body of compressed fluid connecting the diaphragms. 100
13. In an inductive railway signaling system, an induction device, a diaphragm held under the influence of the device, a second diaphragm held away from the influence of 45 the induction device, means whereby a movement of the first diaphragm will cause a corresponding movement in the second diaphragm and circuit making and breaking means operable by the movement of the second diaphragm. 105
14. In an inductive railway signaling system, an induction device, a diaphragm held under the influence of the device, a second diaphragm, a body of fluid connecting the diaphragms and circuit making and breaking 50 means operable by the movement of the second diaphragm. 110
15. In an inductive railway signaling system, a danger signal circuit on the train, a caution signal circuit on the train, a magnet carried by the train, and pneumatic means whereby a variation of the magnetic flux in 55 the space between the poles will operate said circuits selectively. 115
16. In an inductive railway signaling system, a normally closed danger signal circuit on the train, a normally closed caution signal circuit on the train, a magnet carried by the train, a diaphragm held under the influence of the magnet, and means whereby a movement of the diaphragm will open said circuits selectively. 120
17. In an inductive railway signaling system, a normally closed danger signal circuit on the train, a normally closed caution signal circuit on the train, a magnet carried by the train, a diaphragm held under the influence of the magnet, and pneumatic means whereby a movement of the diaphragm will open said circuits selectively. 125
18. In an inductive railway signaling system, a danger signal circuit on the train, a caution signal circuit on the train, an induction device carried by the train, a diaphragm held under the influence of the device, a second diaphragm, and circuit making and breaking means operable by the second diaphragm whereby one of said circuits is opened while the other is maintained closed. 130
19. The combination of a magnet, a casing mounted on the poles of said magnet, and a diaphragm mounted in said casing, whereby a portion at least of said diaphragm may be moved by a variation in the magnetic flux passing between the poles of the magnet. 135
20. The combination of a magnet, a casing mounted on the poles of said magnet, a diaphragm mounted in said casing, whereby a portion at least of said diaphragm may be moved by a variation in the magnetic flux passing between the poles of the magnet, and circuit making and breaking means operable by the movement of said diaphragm. 140
21. In a train control system, the combination of two diaphragms, a train controlling magnet for vibrating one of said diaphragms and a body of fluid connecting the two diaphragms whereby the vibrations of one diaphragm are transmitted to the other. 145
22. In a railway signaling system, a magnet, a diaphragm held under tension by said magnet, and roadside apparatus for selectively reducing or increasing the tension. 150
23. In a railway signaling system, a magnet, a diaphragm disposed within the field of force of said magnet, and roadside apparatus for selectively increasing or decreasing said field of force. 155
24. In a railway signaling system, a train carried magnet, and roadside apparatus for selectively increasing, decreasing or main- 160

taining the flux passing between the poles of the magnet.

25. In a railway signaling system, a train carried magnet, and roadside apparatus operable in accordance with track conditions for selectively increasing, decreasing or maintaining the flux passing between the poles of the magnet.

26. In a railway signalling system, a train carried magnet, and roadside apparatus responsive to track conditions for selectively increasing, decreasing or maintaining the flux passing between the poles of the magnet.

27. In an induction railway signalling system, a train carried magnet, a diaphragm disposed within the attractive influence of the magnet, a roadside inductive apparatus for giving a plurality of indications, and means whereby the attractive influence of the magnet on the diaphragm is selectively varied in accordance with the indication of the inductive apparatus.

28. In an induction railway signalling system, a train carried magnet, a hermetically sealed container mounted on said magnet, a diaphragm mounted in said container, a source of compressed fluid connected to said container, and means whereby a leak in said container will give a danger indication on the train.

29. In an induction railway signalling system, a train carried magnet, a hermetically sealed container mounted on the magnet, another hermetically sealed container, a passage containing compressed air connecting the two containers, and means whereby a leak in the second container will give a danger indication.

Signed at Niagara Falls, in the county of Niagara and State of New York, this 9th day of July A. D. 1926.

THEODORE BODDE.
